UNITED STATES PATENT OFFICE.

NICHOLAS E. RENNAR, OF JERSEY CITY, NEW JERSEY.

SIGNAL DEVICE.

1,165,126.

Specification of Letters Patent. Patented Dec. 21, 1915.

Application filed October 17, 1913. Serial No. 795,617.

To all whom it may concern:

Be it known that I, NICHOLAS E. RENNAR, a citizen of the United States, and resident of Jersey City, in the county of Hudson and State of New Jersey, have invented certain new and useful Improvements in Signal Devices, of which the following is a specification.

This invention relates to a signal device and is particularly adapted to the rear ends of motor vehicles. The organization of the invention includes means for energizing the lamp of the signal device, by the operations of the foot brake pedal, so that the signal is in plain view when the foot brake is set.

In the accompanying drawings Figure 1 represents a plan view of the mechanism and frame of a motor car with the invention attached thereto, Fig. 2 shows an enlarged plan view of the elements of the invention with a fragmentary portion of the motor car, Fig. 3 is a fragmentary right hand side view and section on the line 3, 3 of Fig. 2, Fig. 4 represents a partial front view of Fig. 2, Fig. 5 shows a partial section of Fig. 3 on the line 5, 5 and Fig. 6 shows a modification of a detail.

The frame of the vehicle is shown with the side sills 20, rear cross girder 22, wheels 23 and engine 24. A cross girder 30 has extending therefrom a block 31 of insulating material, with a strip 32 also of insulating material fastened to said block.

A pull rod 33 has extending therefrom the foot pedal 35. The pull rod is pinned to an arm 36 extending from the rocker shaft 37. An arm 38 on the shaft 37 is pinned to the link 39 which latter in turn is pinned to the equalizer bar 40. Pull rods 41 connect the equalizer bar with arms 42 extending from the rocker shaft 43, and the latter operates the foot brakes 44. A pair of collars 46, 47 are fastened to the rod 33.

A movable collar 48 encircles said rod and has formed therewith the toe 49. A pin 50 in the latter collar engages a groove 51 in the rod 33.

A spring 55 encircles the rod 33 and bears between the collar 47 and 48. A flexible U shaped contact piece 56 has one end 57 fastened to the block 32 and the other end 58 is in the path of the toe 49. A stationary contact plate 64 is fastened to the block 32.

From the cross girder 22 extends a bracket 66, which supports a signal box. The said

box is shown with the roof 67, bottom 68, rear wall 69, hinged front frame 70 with the latch 71 and end walls 72. The front frame 70 has supported therein preferably a glass plate 73, which is painted or covered with a non-transparent material. Letters 74 are formed in the paint or non-transparent material to enable light rays to pass therethrough. A slide 75 is guided in lips formed with the hinged front frame.

A source of adjustable illumination, preferably an electric bulb 76 is located in the signal box. The signal box with its bulb and appurtenances I designate a signal.

A source of electric current in this instance electric batteries is shown at 80 from which extend the wires 81, 82, constituting the cable 90. The wire 82 extends to one pole of an electric switch 92 having the handle 93. A wire 94 extends from the other pole of said switch to the contact plate 64. A wire 95 extends from the contact piece 56 and with the wire 82 forms the cable 96. The wires 95 and 81 form the cable 97 which latter extends to the bulb 76. In Fig. 6 the invention is modified by replacing the transparent material 73 by an opaque material 100 in which are formed letters by means of small openings 101.

To use the invention the operator of the motor vehicle bears on the foot pedal 35, which sets the foot brakes 44 in the ordinary way. The handle 93 of the switch being in its closed position, the flexible contact piece 56 is brought in contact with the plate 64 which closes the circuit for the electric bulb 76, and energizes the electric appurtenances thereof to obtain illumination in the signal box and bring the letters on the plate 73 clearly into view. Upon the release of the foot pedal 35 the flexible contact piece 56 separates from the plate 64 and the electric circuit for the bulb is broken and consequently the illumination in the signal box ceases. It will be observed that the foot brakes coat with the illumination in the signal box, so that when the foot brakes are set the signal is in plain view.

The slide 75 is pulled out as shown in Figs. 3 and 6 when the signal is used and closed to prevent injury to the box when said signal is not used. The hinged frame 70 allows the signal box to be opened for the purpose of cleaning and adjustment of the bulb 76.

Having described my invention what I

desire to secure by Letters Patent and claim is:

1. The combination for a vehicle of a signal box, a pull rod in the vehicle, a flexible contact piece with one end thereof supported in the vehicle, a movable collar having a toe supported on the pull rod, flexible means to maintain the said collar in proper position, a stationary contact plate in the path of the free end of the flexible contact piece, a wire for electric current fastened to the stationary contact plate and a wire for electric current fastened to the flexible contact piece, the said wire being connected to the signal box.
2. The combination for a vehicle of a signal box, a pull rod in the vehicle, a flexible contact piece with one end thereof supported in the vehicle, a pair of collars fastened to the pull rod, a movable collar having a toe supported on the pull rod, a spring bearing between the movable collar and one of the collars fastened to the said rod, a stationary contact piece in the path of the free end of the flexible contact piece, a wire for electric current fastened to the stationary contact plate and a wire for electric current fastened to the flexible contact piece, the said

tened to the flexible contact piece, the said wires connected to the signal box.

3. The combination for a vehicle of a signal box, a brake for the vehicle, a pull rod for the brake, a pedal for the pull rod, a girder on the vehicle, a strip of insulating material extending from the girder, a flexible contact piece with one end fastened to said strip, a pair of collars fastened to the pull rod, a movable collar having a toe supported on the pull rod, a spring bearing between the movable collar and one of the collars fastened to the said rod, a stationary contact plate in the path of the free end of the flexible contact piece, a wire for electric current fastened to the stationary contact plate and a wire for electric current fastened to the flexible contact piece, the said wires connected to the signal box.

Signed at the borough of Manhattan in the county of New York and State of New York this 7th day of October A. D. 1913.

NICHOLAS E. RENNAR.
